Filed June 15, 1964, Ser. No. 80,391

Term of patent 14 years

(Cl. D90—20)

Fig. 1

*Fig. 2**Fig. 5**Fig. 4**Fig. 3**Fig. 6*FIG. 1 is a perspective view of a tire embodying our new design, it being understood that the full line portion is repeated throughout the circumference of the tire, shown by means of broken lines;

FIG. 2 is an enlarged fragmentary plan view of the tread portion of the tire shown in FIG. 1;

FIG. 3 is a sectional view taken substantially on the plane indicated by line III—III of FIG. 2, but on a reduced scale;

FIG. 4 is an enlarged fragmentary side elevational view of the outer sidewall portion of the tire illustrated in FIG. 1, but on the same scale as FIG. 3;

FIG. 5 is an enlarged detailed sectional view taken substantially on the plane indicated by line V—V of FIG. 3; and

FIG. 6 is another detailed sectional view taken substantially on line VI—VI of FIG. 3.

The dominant features of our design reside in those portions shown in full lines in the drawings.

We claim:

The ornamental design for a tire, substantially as shown and described.
